UNITED STATES PATENT OFFICE

FORREST LE GRAND BRYANT, OF JOHNSON CITY, NEW YORK, ASSIGNOR TO BRYANT ELECTRIC REFRIGERATOR CORPORATION, OF WILMINGTON, DELAWARE, A CORPORATION OF DELAWARE.

QUICK-MAKE AND QUICK-BREAK SWITCH

Application filed March 10, 1927. Serial No. 174,258.

The invention relates to electrical switches designed primarily for use in the refrigerant circulating systems of electrical refrigerators, a pressure-controlled device known to the trade as a pressure-stat being commonly employed for actuating the switch to control the electric motor.

It is the principal object of the invention to provide a new and improved quick-make and quick-break switch which is rather simple and inexpensive, may be easily adjusted to either make or break contact when desired, and will be proof against arcing.

With the foregoing and minor objects in view, the invention resides in the novel subject matter hereinafter described and claimed, the description being supplemented by the accompanying drawings.

Fig. 1 is a side elevation partly in section of a switch constructed in accordance with my invention, the carrier for the movable contact being shown in readiness for rapid movement to switch-closed position.

Fig. 2 is a view similar to a portion of Fig. 1, but illustrating the switch closed.

Fig. 3 is a duplicate of Fig. 2, with the exception that the parts are shown in switch-open position.

The form of construction illustrated in the accompanying drawings will be rather specifically described, with the understanding however, that within the scope of the invention as claimed, numerous variations may be made.

The numeral 5 designates a horizontal support, upon which a pressure-stat 6 and a housing 7 therefor, are mounted, and 8 denotes a pressure-pipe leading to the pressure-stat for controlling the expansion and contraction of the latter.

A horizontal lever 9 is fulcrumed at 10 upon the housing 7 and is suitably connected at 11 with the upper end of the pressure-stat 6, whereby upward movement of the lever is effected when the pressure-stat expands, and downward movement of said lever is caused upon contraction of said pressure-stat. In order to produce steady movement of the lever, the usual or any preferred stabilizer 12 is associated therewith.

Suitably connected with the support 5 or otherwise mounted under the free end of the lever 9, is an insulating support 13 upon

which a cup 14 of glass or other insulating material rests, said cup containing a quantity of mercury 15 and a covering 16 of oil for said mercury, to prevent arcing as a movable contact 17 enters or leaves the mercury. Preferably, a metal strip 18 extends across the bottom of the cup 14, extends upwardly at 19 at the inner side of the cup wall, is then bent outwardly across the upper edge of this wall as at 20, and extends downwardly at 21, at the outer side of the wall, the lower ends of these downwardly projecting portions being bent outwardly at 22 and formed with openings to receive fasteners 23, by means of which the strip ends may be secured to the support or base 13, thereby serving to secure the cup effectively upon said base. Moreover, the metallic strip acts as a conductor of electricity, between the mercury 15 and one of the necessary wires 24, one of the fasteners 23 being preferably utilized as a binding post for this wire. The other wire 25 may be suitably connected with the movable contact 17.

A carrier 26 is provided for the movable contact 17, said carrier being here shown in the form of a bell crank which is fulcrumed at 28 to the lever 9, in such manner that the horizontal arm 29 of the bell crank may move vertically toward or from the stationary contact means above described. To limit the movement of the carrier 26 with respect to the lever 9, upper and lower stops 30 and 31 have been shown, mounted upon a vertical shank 32 whose upper end may be secured to the lever 9 by means of an appropriate bracket 33.

Means are provided for rapidly completing the movement of the carrier 26 either toward switch-closed or switch-open position, when said carrier has been moved with respect to the lever 9, to a predetermined position, and provision is made for moving the carrier 26 to said predetermined position, as said lever swings toward or from the stationary contact means.

In the present showing, the vertical arm 34 of the contact carrier 26, is provided with a track 35 elongated in a direction transverse to the pivot or fulcrum 28. This track embodies two cams 36 and 36* converging to a crest 37. A spring-actuated shoe is co-operable with the track 35 to rap-

idly complete the movement of the carrier 26 in either direction, when it has been moved into the relation with the lever 9, shown in Fig. 1. In the present embodiment of the invention, 38 denotes a roller co-operable with the track 35 and mounted on an arm 39, this arm being pivoted at 40 to a standard 41 secured to the lever 9. A coil spring 42 is shown, connecting the arm 16 39 with the lever 9 to forcibly hold the roller against the track 35. When the switch stands closed as seen in Fig. 2 and the lever 9 swings downwardly under the action of the pressure-stat 6, the carrier 26 is gradually rocked to the position shown in Fig. 1, the cam 36^a in the meantime raising the arm 39 against the action of the spring 42 and placing the latter under additional tension. Hence, as soon as the crest 37 moves 20 a very slight amount past a dead-center position, the spring 42 will downwardly snap the arm 39, causing the roller 38 to co-act with the cam 36, in rapidly swinging the carrier 26 to the position of Fig. 3, thereby 25 quickly opening the switch, as shown in this last named view. During upward swinging of the lever 9, the contact carrier 26 is moved to the position of Fig. 1, so that the roller 38 and the cam 36^a will 30 at the proper time, co-operate in rapidly swinging said carrier to the switch-closed position of Fig. 2. In this position, the carrier end 29 engages the stop 31, and said end contacts with the stop 30, when the carrier moves to the switch-open position of 35 Fig. 3.

The means for moving the carrier 26 into the relation with the lever 9, shown in Fig. 1, preferably embodies upper and lower trips 40 43-44, and a lateral lug 45 on the carrier 26, the lug being positioned between the trips, as shown. These trips are stationarily mounted, being preferably in the form 45 of screws threaded adjustably through portions of an appropriate carrying standard or the like 46, rising from the support 5. The trips or screws 43-44 may be adjusted to cause opening or closing of the switch at predetermined points of the travel of the lever 9, and they may be locked in adjusted position by suitable means, such as the lock nuts 43^a and 44^a.

As the lever 9 descends from the position 55 of Fig. 2, the lug 45 will engage the lower trip 44 and hence the carrier 26 will be gradually swung to the position at which the track 35 and the co-acting shoe, act to rapidly complete the switch-opening movement of said carrier. Similarly, upon upward movement from the switch-open position of Fig. 3, effected by upward swinging 60 of the lever 9, the lug 45 will engage the upper trip 43 and hence said lug and trip will co-operate in swinging the carrier 26 65 with respect to said lever 9 to the point

at which the coacting shoe and track will function to rapidly complete the switch-closing movement of the carrier.

As excellent results may be obtained from the general construction herein disclosed, it 70 may be followed if desired. However, the present disclosure is for illustrative purposes only, and within the scope of the invention as claimed, variations may be made, as above stated. 75

I claim:—

1. A quick make and quick break switch comprising stationary contact means, a member mounted for movement toward or from said contact means, a movable contact for co-action with said stationary contact means, a carrier for said movable contact, means mounting said carrier on said member for movement with respect thereto toward or from said stationary contact means, 80 means for rapidly completing the movement of said carrier in either direction upon movement thereof to a predetermined position with respect to said member, and means for automatically moving said carrier to 85 said predetermined position as the aforesaid member is moved toward or from said stationary contact means.

2. A quick make and quick break switch comprising stationary contact means, a 90 member mounted for movement toward or from said contact means, a movable contact for co-action with said stationary contact means, a carrier for said movable contact, means mounting said carrier on said member for movement with respect thereto toward or from said stationary contact means, 95 means for rapidly completing the movement of said carrier in either direction upon movement thereof to a predetermined position with respect to said member, and two 100 stationary trips for effecting movement of said carrier to said predetermined position, said trips being individually active on said carrier as the latter is moved by the aforesaid member. 105

3. A quick make and quick break switch comprising stationary contact means, a member mounted for movement toward or from said contact means, a movable contact 110 for co-action with said stationary contact means, a carrier for said movable contact, means pivoting said carrier to said member for movement with respect thereto toward or from said stationary contact means, 115 spring-actuated means for rapidly completing the movement of said carrier in either direction upon movement thereof to a predetermined position with respect to said member, and means for automatically moving 120 said carrier to said predetermined position as said member is moved toward or from the stationary contact means.

4. A quick make and quick break switch comprising stationary contact means, a 125

4
carrier for movement into or from the afore-
said mercury, means for rapidly completing
the movement of said carrier in either di-
rection after movement thereof to a prede-
termined position with respect to the lever,
and means for automatically moving said
carrier to said predetermined position as the
aforesaid lever is moved in one direction or
the other.

10 12. In a switch contact, an insulating cup
to contain mercury, and strip metal extend-

ing vertically at the exterior of the cup, bent
inwardly over the upper edge of said cup,
and extending downwardly into its mer-
cury-containing portion, the lower end of 15
the strip metal being laterally bent and ap-
ertured to receive a fastener by means of
which the cup and strip metal may be held
upon a support.

In testimony whereof I have hereunto af- 20
fixed my signature.

FORREST LE GRAND BRYANT.
